United States Patent Office

Des. 203,108
Patented Dec. 7, 1965

203,108

HAND TRUCK

Melvin Cohen, 150 Dayton Ave., Passaic, N.J.

Filed Mar. 11, 1963, Ser. No. 73,912

Term of patent 14 years

(Cl. D14—3)

FIG. 1 is a perspective view of a hand truck showing my new design;

FIG. 2 is a front elevational view thereof;

FIG. 3 is a rear elevational view thereof;

FIG. 4 is a top plan view thereof; and

FIG. 5 is a bottom plan view thereof.

I claim:

The ornamental design for a hand truck, as shown.
